(57) **ABSTRACT**

A self-balancing golf club with rearward lean. The self-balancing golf putter includes a club head. The club head includes a clubface configured to make contact with a golf ball. The self-balancing golf putter also includes a shaft attached to the club head. The shaft includes a center axis, wherein the center axis converges with a balance point configured to make the club face seek square when making contact with the golf ball.

SELF-BALANCING GOLF CLUB WITH REARWARD LEANING SHAFT

CROSS-REFERENCE TO RELATED APPLICATIONS

This application is a continuation-in-part of, and claims the benefit of and priority to: (1) U.S. Non-Provisional patent application Ser. No. 13/865,708 filed on Apr. 18, 2013 (U.S. Pat. No. 9,233,280); (2) U.S. Non-Provisional patent application Ser. No. 14/219,929 filed on Mar. 19, 2014 (U.S. Pat. No. 8,932,148); and (3) U.S. Non-Provisional patent application Ser. No. 14/534,308 filed on Nov. 6, 2104, all of which applications are incorporated herein by reference in their entirety.

BACKGROUND OF THE INVENTION

When a golf club is not self-balancing, the golfer must balance the club in his/her stroke. That is, the golfer must put torque on the shaft in order to keep the face of the golf club square to the arc. This puts strain on the hands and arms of the golfer and makes it more difficult for the golfer to hit or putt successfully. Further, it means that the golfer must adjust to each golf club independently, because the amount and direction of torque required to square the golf club will vary depending on the golf club.

In order to be self-balancing a golf club must satisfy two conditions. It must “seek” square to the arc during a normal swing and it must do so when the shaft includes a forward lean. Many golf clubs claim to be self-balancing, however, they do so only when the shaft does not include forward lean. Since most golfers have forward lean in the shaft of their golf clubs, whether the golf club self-balances is irrelevant because it does not do so when in actual use.

A golf club can also be self-balancing when it is configured with rearward lean. Such a club requires additional design considerations relative to a forward leaning club, particularly with respect to the location of the attachment of the base of the shaft to the club head. Rearward lean is particularly useful for “face-on” or “side-saddle” putting where shaft length is greater than approximately 37 inches.

In addition, golf club grips do not conform well to the hands of the user. In particular, most club grips are round in shape. However, the hands of the user do not form a round shape. Therefore, the hands of the user must conform to the grip and there are areas of the grip with little or no pressure and areas of the grip with high pressure. Moreover, a round grip does not provide any type of tactile feedback to indicate to the user whether the club is properly aligned.

Accordingly, there is a need in the art for a golf club that will seek square with forward lean or rearward lean. Further, there is a need for the golf club to avoid putting torque or strain on the user. In addition, there is a need for the club to have a grip that conforms to the hands of the user and provides tactile feedback as to the correct alignment of the golf club. And, there is a need for the club grip to compensate for the lean angle of the club shaft to the club face irrespective of the location of placement of the hands along the grip.

Brief Summary of Example Embodiments

This Summary is provided to introduce a selection of concepts in a simplified form that are further described below in the Detailed Description. This Summary is not intended to identify key features or essential characteristics

of the claimed subject matter, nor is it intended to be used as an aid in determining the scope of the claimed subject matter.

One example embodiment includes a golf club. The golf club includes a club head. The club head includes a clubface configured to make contact with a golf ball. The golf club also includes a shaft attached to the club head. The shaft includes a center axis. The golf club further includes a grip which has a shape that can accommodate an angled channel, and may for example be elongated in an elliptical in shape, wherein the elongated grip includes a center axis. A hollow channel in the grip within which the shaft fits has a center axis that is: (a) non-parallel to the center axis of the grip when viewed from a point on the y-axis, (b) parallel to the center axis of the grip when viewed from a point on the x-axis; and (c) parallel to a major axis through the focal points of the elongated shaped grip.

Another example embodiment includes a golf club. The golf club includes a club head. The club head includes a clubface configured to make contact with a golf ball. The golf club also includes a shaft attached to the club head. The shaft includes a center axis, wherein the center axis converges with a balance point at an intersection of a lie angle radian and a lie angle axis. The golf club further includes a grip which has an angled channel, and may for example be elongated and elliptical in shape, wherein the grip includes a center axis through the length of the grip. A hollow channel in an elliptically shaped grip within which the shaft fits has a center axis that is: (a) non-parallel to the center axis of the grip when viewed from a point on the y-axis, (b) parallel to the center axis of the grip when viewed from a point on the x-axis; and (c) parallel to a major axis through the focal points of the elongated shaped grip.

Another example embodiment includes a golf club. The golf club includes a club head. The club head includes a clubface configured to make contact with a golf ball. The golf club also includes a shaft attached to the club head. The shaft includes a center axis, wherein the center axis converges with a balance point at an intersection of a lie angle radian and a lie angle axis. The balance point is at a position $(x=\pm x_1, y=+y_1, z=z_1)$ in an imaginary Cartesian coordinate system defined around the club head. The imaginary Cartesian coordinate system includes an origin at the center of gravity of the club head and an x-axis defined as a horizontal line through the origin between the toe of the club head and the heel of the club head, where the clubface has a negative x location; The imaginary Cartesian coordinate system also includes a y-axis defined as a horizontal line through the original parallel to the clubface, where the heel of the club head has a negative y location for a right-handed player. The imaginary Cartesian coordinate system further includes a z-axis defined as a vertical line through the origin, where the top of the shaft has a positive z location. The position z_1 is the vertical distance between the origin and the attachment surface of the club head. The imaginary Cartesian coordinate system additionally includes a lie angle plane defined by the center axis of the shaft and a line parallel to the x-axis, wherein the line parallel to the x-axis is offset from the x-axis a distance z_2 along the z-axis. The imaginary Cartesian coordinate system further includes a radian plane parallel to the x-y plane offset a distance z_1 from the x-y plane, where the lie angle axis includes the intersection of the lie angle plane and the radian plane. The value of y_1 is calculated using the equation

$$y_1 = \left| \frac{Z_2 - Z_1}{\tan \alpha} \right|.$$

Where α_2 is the lie angle of the center axis. The value of x_1 is calculated using the equation

$$x_1 = \left| \frac{Z_2 - Z_1}{\tan^2 \alpha} \right|.$$

The golf club further includes a grip with dimensions such that the grip accommodates an angled channel within which the club shaft fits. The grip may, for example, be circular, square, elliptical, rectangular, triangular, or any number of other shapes. The shape may have one or more flat sides, or be a shape that is generally stretched. An elongated shape provides a cross section of the grip with a first dimension along a first axis being relatively longer than a second dimension along a second axis that is generally perpendicular to the first axis. In an embodiment of the invention with an elongated grip, a center axis is positioned through the length. In an elongated embodiment, a hollow channel in the grip within which the shaft fits has a center axis that is: (a) non-parallel to the center axis of the grip when viewed from a point on the y-axis, (b) parallel to the center axis of the grip when viewed from a point on the x-axis; and (c) parallel to a major axis through the focal points of the elongated shaped grip.

Another example embodiment includes a golf club. The golf club includes a club head. The club head includes a clubface configured to make contact with a golf ball. The golf club also includes a shaft attached to the club head. The shaft includes a center axis, wherein the center axis converges with a balance point at an intersection of a lie angle radian and a lie angle axis. The golf club further includes a grip which may for example be elongated in shape, wherein the elongated grip includes a center axis. A hollow channel in the grip within which the shaft fits has a center axis that is (a) non-parallel to the center axis of the grip when viewed from a point on the y-axis, (b) parallel to the center axis of the grip when viewed from a point on the x-axis; and (c) parallel to a major axis through the focal points of the elongated shaped grip.

These and other objects and features of the present invention will become more fully apparent from the following description and appended claims, or may be learned by the practice of the invention as set forth hereinafter.

BRIEF DESCRIPTION OF THE DRAWINGS

To further clarify various aspects of some example embodiments of the present invention, a more particular description of the invention will be rendered by reference to specific embodiments thereof which are illustrated in the appended drawings. It is appreciated that these drawings depict only illustrated embodiments of the invention and are therefore not to be considered limiting of its scope. The invention will be described and explained with additional specificity and detail through the use of the accompanying drawings in which:

FIG. 1 illustrates an example of a self-balancing putter;

FIG. 2 illustrates the self-balancing putter of FIG. 1 looking down the x-axis at the face of the putter;

FIG. 3 illustrates a self-balancing putter with a lie angle plane;

FIGS. 4A-B illustrate top views of the self-balancing putter with forward and rearward leaning shafts, respectively;

FIGS. 5A-B illustrate side views of the self-balancing putter with forward and rearward leaning shafts, respectively;

FIG. 6A illustrates a bottom view of the example of an elliptical grip;

FIG. 6B illustrates a side view of the example of an elliptical grip;

FIG. 6C illustrates a front view of the example of an elliptical grip;

FIG. 7 illustrates a self-balancing putter looking down the x-axis at the face of the putter with a grip having a hollow channel parallel to the center axis of the grip;

FIGS. 8A-B illustrate a self-balancing putter with forward lean and rearward lean, respectively, looking down the y-axis at the face of the putter with a grip having a hollow channel non-parallel to the center axis of the grip;

FIG. 9 illustrates a perspective view of the putter from the top of the elliptical grip;

FIGS. 10A-F illustrate six different club grips with club shafts having different forward lean angles;

FIGS. 10G-L illustrate six different club grips with club shafts having different rearward lean angles; and

FIGS. 11A-H illustrate eight different club grip cross-sectional shapes.

DETAILED DESCRIPTION OF SOME EXAMPLE EMBODIMENTS

Reference will now be made to the figures wherein like structures will be provided with like reference designations. It is understood that the figures are diagrammatic and schematic representations of some embodiments of the invention, and are not limiting of the present invention, nor are they necessarily drawn to scale.

FIG. 1 illustrates an example of a self-balancing putter 100. A self-balancing putter 100 is a club used in the sport 40 of golf to make relatively short and low-speed strokes with the intention of rolling the ball into the hole. It is differentiated from the other clubs (typically irons and woods) by a club head with a very flat, low-profile, low-loft striking face, and by other features which are only allowed on putters 100, 45 such as bent shafts, non-circular grips, and positional guides. Putters 100 are generally used from very close distances to the cup, generally on the putting green, though certain courses have fringes and roughs near the green which are also suitable for putting. Although a putter is used as 50 exemplary herein, one of skill in the art will appreciate that the principles disclosed herein can be used in any golf club.

FIG. 1 shows an artificial coordinate system 102 about the putter head 100. The origin on the Cartesian coordinate system 102 (i.e., the position $x=0, y=0, z=0$) is the center of 55 mass (center of gravity) of the putter head 100. In physics, the center of mass of a distribution of mass in space is the unique point where the weighted relative position of the distributed mass sums to zero. I.e., the distribution of mass is balanced around the center of mass and the average of the 60 weighted position coordinates of the distributed mass defines its coordinates.

FIG. 1 shows that the coordinate system 102 includes an x-axis 104a, a y-axis 104b and a z-axis 104c. The x-axis 104a runs through the face of the self-balancing putter. The 65 face of the self-balancing putter 100 has a negative x position. The x-axis 104b is parallel to the face of the self-balancing putter 100. That is, the y-axis 104b is parallel

to a line drawn to the center of one side of the face to the center of the other side of the face (if the clubface is symmetrical), such that the y-z plane (plane defined by the y-axis **104b** and z-axis **104c**) is parallel to the face of the self-balancing putter **100**. The heel and toe of the self-balancing putter **100** have negative and positive y positions, respectively (vice versa for a left handed player). I.e., the heel is always closest to the player (for a right handed player this is always a negative y position, and for a left handed player this is always a positive y position). The z-axis **104c** runs vertically through the center of gravity of the self-balancing putter **100**. The top of the self-balancing putter **100** (e.g., top of the shaft, grip, etc.) has a positive z position. I.e., it is above the x-y plane.

FIG. 2 illustrates the self-balancing putter **100** of FIG. 1 looking down the x-axis at the face of the putter. The lie angle **202** ("a 2") is defined as the angle formed between the center axis **204** of the shaft **106** and the sole, or ground line, of the self-balancing putter **100** when the self-balancing putter **100** is soled (flat on the ground) in its proper playing position (as at address), i.e., when the self-balancing putter **100** is soled on flat ground, with a straight line extending back from the heel of the self-balancing putter **100** along the ground (either the y-axis **104b** or a line parallel to the y-axis **104b**). The lie angle **202** is the angle from that line up to the shaft. That is, in the coordinate system **102** defined in FIG. 1, the lie angle **202** is the angle between the x-y plane and the axis **204** of the shaft **106** through the center point of the shaft **106**. There is no "correct" or standard lie angle **202**; the lie angle **202** that works for one golfer might be the wrong lie angle **202** for another golfer. The arc (vertical and horizontal) of a pendulum putting stroke is created by the lie angle **202** and length of the shaft. The flatter the lie angle **202** the more the same pendulum stroke appears to be inside to inside and the more upright the shaft lie angle **202** the more the putter head appears to swing back and down the line. The USGA has limited the upright lie angle **202** of a putter to be at least 10° off 90°.

FIG. 3 illustrates a self-balancing putter **100** with a lie angle plane **302**. The lie angle plane **302** is a plane defined by the axis of the shaft **106** through the center point of the shaft and a line parallel to the x-axis **104a** of FIG. 1 (i.e., a line parallel to the x-axis **104a** and offset some amount along the z-axis **104c** ("z₁")). That is, the lie angle plane **302** is similar to the x-y plane of FIG. 1 rotated about the x-axis **104a** by the lie angle then offset along the z-axis **104c** by the distance z₁. The value of z₁ can be a positive number, zero, or a negative number, i.e., the lie angle plane **302** is set at a specific distance from the center of mass. For example, the distance z₁ can be between 0.4 inches and 0.6 inches. E.g., the distance z₁ can be approximately 0.5 inches. As used in the specification and claims, the term approximately shall mean that the value is within 10% of the stated value, unless otherwise specified. One of skill in the art will appreciate that the center line of the shaft **106** with the specified lie angle must rest in the lie angle plane **302**.

A radian plane **304** is also defined in FIG. 3. The radian plane **304** is parallel to the x-y plane of FIG. 1 and offset relative to the x-y plane of FIG. 1 by some distance ("z₂"), i.e., it is a plane with any x or y position but with constant z position of z₂. The distance z₂ is the vertical distance from the origin to the attachment surface. The distance z₂ can include a negative number, zero, or positive number. One of

skill in the art will appreciate that the distance between the lie angle plane **302** and the radian plane **304** along the z-axis of FIG. 1 will be: z₁-z₂.

Equation 1

$$z_{total} = z_1 - z_2$$

5 FIG. 3 further shows a lie angle axis **306**. The lie angle axis **306** is defined by the intersection of the lie angle plane **302** with the radian plane **304**. That is, the lie angle axis **306** is a line parallel to the x-axis **104a** of FIG. 1 but offset some distance along the y-axis **104b** ("y₁") and a distance of z₂ along the z-axis **104c**. The distance y₁ can be a negative number, positive number or zero and the distance y₁ need not be the same distance as distance z₂. Therefore, the position of the lie angle axis **306** will have any x value and is defined by the coordinates (y=y₁, z=z₂). One of skill in the art will appreciate that since the z-axis **104c** of FIG. 1, the lie angle plane **302** and the radian plane **304** having a value of α_1 , the value of y₁ can be calculated using the formula:

$$20 \tan \alpha = \frac{Z_{total}}{y_1} \text{ yields } y_1 = \left| \frac{Z_{total}}{\tan \alpha} \right| \quad \text{Equation 2}$$

FIG. 4A illustrates a top view (i.e., down the z-axis) of the self-balancing putter **100**. For simplicity's sake, the shaft of the putter is not shown in FIG. 4A, but it should be understood, that the shaft would be affixed to the putter head at balance point **404a**. FIG. 4B also illustrates a top view (i.e., down the z-axis) of the self-balancing putter **100**. As with FIG. 4A, the shaft of the putter is not shown in FIG. 4B, but again it should be understood, that the shaft would be affixed to the putter head at balance point **404b**. In addition, the quadrants of the x-y plane are labeled. The z-axis is not shown but passes through FIG. 4A as can be determined from FIG. 1.

35 FIGS. 4A-B show two different lie angle radians **402a**, **402b** where lie angle radian **402a** has a forward leaning shaft and lie angle radian **402b** has a rearward leaning shaft. A rearward leaning shaft is preferred for face-on or side saddle putting in which a longer putter shaft of more than approximately 37 inches or so is typically employed. For both configurations, the balancing concepts are the same. The lie angle radian **402** origin is the z-axis (x=0, y=0) on the radian plane **304**. The angle relative to the x-axis **104a** of the lie angle radian **402** is always approximately equal to the lie angle. The lie angle radian **402** terminates at the lie angle axis **306**. That is, the lie angle radian **402** is similar to the x-axis, offset along the z-axis by the same distance as the radian plane (z₂) and rotated by the lie angle (or the y-axis rotated by 90 degrees minus the lie angle) in a direction from the positive x-axis **104a** to the positive y-axis **104b** (or the negative y-axis **104b** for a left-handed player). The lie angle radian **402** always terminates at the lie angle axis at a position (x=±x₁, y=±y₁) (the absolute value in Equation 2 ensures that the value of y₁ is always positive regardless of the z value). Right-handed players always have the lie angle radian **402** in the +x, +y quadrant, and left-handed players always have the lie angle radian **402** in the +x, -y quadrant. One of skill in the art will appreciate that, because the x-axis **104a**, lie angle radian and line segment of distance y₁ can form a right triangle, the value of x₁ can be calculated using the formula:

$$65 \tan \alpha = \frac{y_1}{x_1} \text{ yields } x_1 = \frac{y_1}{\tan \alpha} \quad \text{Equation 3}$$

Substituting Equation 2 into Equation 3 yields:

$$x_1 = \left| \frac{Z_{total}}{\tan \alpha} \right| = \left| \frac{Z_{total}}{\tan^2 \alpha} \right| \quad \text{Equation 4}$$

or

$$x_1 = \left| \frac{y_1}{\frac{Z_{total}}{y_1}} \right| = \left| \frac{y_1^2}{Z_{total}} \right|$$

The shaft center line always originates at a balance point 404 defined as the intersection of the lie angle radian 402 and the lie angle axis 306 (i.e., position $x=\pm x_1$, $y=\pm y_1$, $z=z_2$). That is, the axis of the shaft through the center of the shaft (the same axis used to measure the lie angle), the lie angle axis 306 and the lie angle radian 402 all converge at a single point. One of skill in the art will appreciate that the shaft can be rotated about this point. I.e., the axis of the shaft can be moved within the lie angle plane 302 (otherwise, the lie angle would be changed) as long as the balance point 404 remains the same. This can allow the self-balancing putter 100 to be customized to the user based on the lie angle preferred by the user. The balance point is configured to make the club face seek square when making contact with the golf ball. As used in the specification and the claims, the phrase "configured to" denotes an actual state of configuration that fundamentally ties recited elements to the physical characteristics of the recited structure. As a result, the phrase "configured to" reaches well beyond merely describing functional language or intended use since the phrase actively recites an actual state of configuration.

One of skill in the art will appreciate that the shaft may, but is not required to, attach to the balance point 404 (even though the center line of the shaft will still intersect with the balance point 404). In particular, the shaft may have a bend or curve near the balance point 404. Thus the lie angle axis 306 of FIG. 3 is not necessarily contiguous with the shaft. Additionally or alternatively, the shaft can be attached to a hosel. The hosel is a portion of the self-balancing putter 100 head to which the shaft attaches. Though largely ignored by players, hosel design is integral to the balance, feel and power of a self-balancing putter 100. A hosel can be a separate piece attached to the club head and can connect to the shaft internally or externally and it can be bent. In addition the rules of golf consider a bend in the shaft to be a type of hosel.

Because the balance point 404 is the intersection of the lie angle axis 306 and the lie angle radian 402, the putter head will be balanced to match the lie angle of the shaft relative to the ground line. This is critical to keep the face square to the arc of the stroke without any outside influences or any torsion forces from the golfer's hands.

The balance point 404 at the intersection of the lie angle axis 306 and the lie angle radian 402, with shaft lean that is either forward or rearward in direction, will keep the putter face perpendicular to the arc that the lie angle and length creates throughout the back swing, transition and forward stroke and impact. If the shaft attaches at a different point, the self-balancing putter 100 is not swung on the lie angle that the shaft creates (which is limited to 80° upright, as described above). This eliminates the possibility of a toe down or variations thereof, toe up or variations thereof, face balanced or variations thereof or face straight down self-balancing putter 100 ever being able to remain naturally

balanced face on and perpendicular to the arc the self-balancing putter 100 swings on without outside influence from the hands.

The benefit of this balancing is to keep the face square to the arc without tension or manipulation of the large and small muscles in the arms and hands. Being able to reduce tension in your hands and arms allows a golfer to focus on acceleration for proper distance control without also thinking about face angle (direction and path) at impact, i.e., by inserting or aligning the shaft not directly above the center of mass it creates an extra lever that resists twisting on any strike and in fact self corrects without any outside influence from your hands. In other words, the balance point 404 ensures that the self-balancing putter 100 seeks 'square' with an appropriate shaft lean at address and continues to seek square at any point in the back swing, down swing and impact.

FIG. 5A illustrates a side view (i.e., down the y-axis) of the self-balancing putter 100. FIG. 5A shows a forward lean 20 of the shaft 106. The shaft 106 lies entirely in the lie angle plane 302 of FIG. 3, i.e., the shaft 106 is in the lie angle plane 302 and starts 90 degrees to the lie angle axis (which is parallel to the x-axis 104a). The shaft 106 is tilted from this position toward the face of the self-balancing putter 100 25 under current golf rules. This tilt is called forward lean and typically is moved forward so the top center line end point of the shaft is approximately 0.75 inches behind the face of the self-balancing putter 100 (about 1.7 degrees) but is not limited to that. In this configuration, a shaft with forward lean is in the lower front quadrant (+x, +y) as shown in FIG. 4A.

As described above, it is also possible to achieve a self-balancing putter 100 that seeks square and that has a rearward leaning shaft. This is particularly useful for putters 35 known as face-on or side saddle putters having longer shafts measuring approximately 37 inches or more. FIG. 5B illustrates a side view (i.e., down the y-axis) of the self-balancing putter 100 with a rearward leaning shaft 106. As in the embodiment of FIG. 5A with a forward leaning shaft, the self-balancing putter 100 has a shaft 106 that lies entirely in the lie angle plane 302 of FIG. 3, i.e., the shaft 106 is in the lie angle plane 302 and starts 90 degrees to the lie angle axis (which is parallel to the x-axis 104a). The shaft 106 in this embodiment is tilted from this position away from the face 40 of the self-balancing putter 100 under current golf rules. This tilt is called rearward lean and is angled in a rearward direction so the top center line end point of the connection point of the shaft is closer to the putter face than a similarly shaped forward leaning shaft with the same center of gravity.

The actual measured distance between the connection point and the face varies depending on the shape of the putter. The shaft is in the range of approximately 38-45 inches long. This results in the rearward shaft angle lean being in the range of approximately 1/2 to 10 degrees which are the limits 50 prescribed by the USGA. It should be understood that even for golf club shafts with measurements outside these ranges, the invention would still function. For clubs having these characteristics, the shaft with rearward lean is in the upper front quadrant (-x, +y) as shown in FIG. 4B. In either case, 55 the center of gravity is still located under the z-axis of the shaft.

The benefit of a rearward leaning shaft is for use with side saddle putting so the putter head is positioned in front of the golfer's lead foot and so that the golfer is able to use 60 stereoscopic vision.

FIGS. 6A, 6B and 6C illustrate an example of an elongated grip that is generally elliptical in shape. FIG. 6A

illustrates a bottom view of the example of an elliptical grip 600; FIG. 6B illustrates a side view of the example of an elliptical grip; and FIG. 6C illustrates a front view of the example of an elliptical grip. The elliptical grip 600 can provide a better grip surface for a user because it is elongated, i.e., the elliptical grip 600 better conforms to the hand of the user during actual use. Additionally or alternatively, the elliptical grip 600 helps the putter to self-align better. That is, the elliptical grip 600 allows the club to be aligned in the user's hand more naturally, providing for a more reproducible stance and, therefore, more consistent putting.

In mathematics, an ellipse is a curve on a plane surrounding two focal points such that a straight line drawn from one of the focal points to any point on the curve and then back to the other focal point has the same length for every point on the curve. The shape of an ellipse (how "elongated" it is) is represented by its eccentricity which for an ellipse can be any number from 0 (the limiting case of a circle) to arbitrarily close to but less than 1. Ellipses are the closed type of conic section: a plane curve that results from the intersection of a cone by a plane. Other elongated shapes (e.g. triangular, rectangular, other non-conforming shapes such as generally elliptical with one or more flat sides), may be substituted for an elliptical shape. For purposes of this application, an elliptical grip will be described and shown. However, it should be understood that other elongated shapes as specified herein may be substituted for the elliptical grip.

FIGS. 6A-C show that the elliptical grip 600 includes a major axis 602a and a minor axis 602b (collectively "axes 602") which intersect at a center axis 604. Ellipses have two mutually perpendicular axes about which the ellipse is symmetric. These axes intersect at the center axis 604 of the ellipse due to this symmetry. The larger of these two axes, which corresponds to the largest distance between antipodal points on the ellipse, is called the major axis 602a or transverse diameter. The smaller of these two axes, and the smallest distance across the ellipse, is called the minor axis 602b or conjugate diameter. One of skill in the art will appreciate that the ellipse can include one or more flat sections, i.e., a portion of the elliptical grip 600 can have a portion of the ellipse which is linear rather than curved.

The major axis 602a can be perpendicular to the club face (i.e., parallel to the x-z plane defined by the x-axis 104a and the z-axis 104c of FIG. 1). The maximum diameter of the major axis 602a is 1.750 inches under current USGA rules. Typically, the major axis 602a will have a diameter between 0.5 inches and 1.750 inches. This size can be critical to fit comfortably within the hand of the user.

The minor axis 602b can be parallel to the club face (i.e., parallel to the y-z plane defined by the y-axis 104b and the z-axis 104c of FIG. 1). Typically, the minor axis 602b will have a diameter of between 0.95 inches and 1.35 inches. For example, the minor axis 602b can be approximately 1.15 inches long. This size can be critical to fit comfortably within the hand of the user.

FIG. 6 shows that center axis 204 of the shaft 106 can be offset relative to the center axis 604 of the elliptical grip 600. That is, the center axis 204 and the center axis 604 are non-parallel to one another, i.e., the center axis 204 is not aligned with or parallel to, but may intersect, the center axis 604. For example, the center axis 604 and the center axis 204 can intersect approximately halfway between the top and the bottom of the elliptical grip. For example, if the elliptical grip is approximately 10.5 inches long, then the center axis 204 and the center axis 604 can intersect approximately 5.25 inches from the bottom of the elliptical grip 600. The angle

of the center axis 604 relative to the center axis 204 can be any value in a broad range of values that is, for most practical purposes, between 0.5 degrees and 20 degrees. In setting the angle, it is desirable to consider the length of the putter shaft since the combination of length and angle determines the position of the grip over the putter face. A shorter putter shaft is typically used with a greater angle than a longer putter shaft. In one embodiment, for example, the angle of the center axis 604 relative to the center axis 204 is approximately 1.5 degrees. The center axis 204 may be on the major axis 602a (in that case the center axis 204 and the center axis 604 coincide with one another when viewed from the side, such as in FIG. 6B), i.e., each point of the center axis 604 where the shaft 106 is within the elliptical grip 600 may be on the major axis 604.

Golf is a game of "feel" in terms of the manner that a player holds and swings the club, and the force imparted by the player with which the clubface impacts the ball. This is true for any club, but particularly for a putter. Putting requires exacting precision. The lie angle of the putter clubface and the position of the hands on the grip vary each time a player sets up to take a putt. This is further complicated by the fact that players typically hold the putter at different positions along the grip depending on the length of the putt—lower down for a short putt and higher up for a long putt. In practice, a shorter, softer stroke is typically applied to a short putt while a longer, harder stroke is typically applied to a long putt. Each time a player holds the club, there is some degree of variation in the placement of the hands along the length of the grip. That being the case, it is desirable to provide a club that exactly replicates the angle of the club face to the ball irrespective of the position along the length of the grip at which the player holds the club. Grip 600 achieves this result.

FIG. 7 shows the same view of the self-balancing putter as in FIG. 2, looking down x-axis 104a at the face of the putter. In this view, center axis 604 of elliptical grip 600 within which shaft 106 is inserted is parallel to center axis 204 of shaft 106.

FIGS. 8A-B show the same view of the self-balancing putter as in FIGS. 5A-B with forward lean and rearward lean respectively, looking down the y-axis 104b at a 90 degree angle from that of FIG. 7. In these views, center axis 604 of elliptical grip 600 within which shaft 106 is inserted at an angle to center axis 604 is non-parallel to center axis 204 of shaft 106. In other words center axis 604 of grip 600 and center axis 204 of shaft 106 are non-parallel.

FIG. 9 is a top down perspective view of the putter from the top of the elliptical grip 600, approximately looking down z-axis 104c. In this view, it can be seen that shaft 106 is angled within grip 600 so that the exit point of shaft 106 from the bottom of grip 600 is towards back edge 905 of grip 600 where major axis 602a is approximately parallel to x-axis 104a and perpendicular to y-axis 104b. And, the top of shaft 106 is at a front edge 910 of grip 600.

The three views of elliptical grip 600 on shaft 106 as shown in FIGS. 7-9, looking down the respective axes (x-axis 104a in FIG. 7; y-axis 104b in FIG. 8; and z-axis 104c in FIG. 9) show together that center axis 604 of elliptical grip 600 within which shaft 106 is inserted is: (a) non-parallel to center axis 204 of shaft 106 when viewed from a point on the y-axis, (b) parallel to center axis 204 of shaft 106 when viewed from a point on the x-axis; and (c) parallel to major axis 602a through the focal points of elliptically shaped grip 600. This is important within the context of a golf club putter because as a player moves their hands to hold grip 600 at any point along the length of grip

11

600, the angles remain the same relative to the clubface. In particular, the angle between a plane through center axis 204 and the x-y plane remains the same, and the angle between a plane through center axis 604 of grip 600 and the x-y plane remain the same. This results in the lie angle staying constant regardless of the position along grip 600 that the player holds the club. This configuration permits the player to replicate swing dynamics every time they swing the club regardless of the position of the hands along grip 600.

The particular angle between center axis 604 of grip 600 and center axis 204 of shaft 106 depends on the lean of shaft 204. The lean may be forward towards the face of the club or rearward away from the face of the club. As an example, the club shown in FIGS. 7, 8A and 9 has a slight forward lean which can be seen in FIGS. 8A and 9 (but not in FIG. 7), while the club shown in FIG. 8B has a rearward lean. In FIGS. 10A-F, six different putters with different forward lean angles of 1° (FIG. 10A), 2° (FIG. 10B), 3° (FIG. 10C), 4° (FIG. 10D), 5° (FIG. 10E) and 6° (FIG. 10F) are shown. FIGS. 10G-L show the channel within grip 600 angled in a rearward direction to provide a backward lean of 1°-6° degrees, respectively. In each of FIGS. 10A-L, the angle between center axis 604 of grip 600 and center axis 204 of shaft 106 is offset such that the sides of grip 600 as indicated by reference line 1010 extending down from the side of grip 600 are parallel to y-axis 104b and to face 1005 of the putter. This configuration achieves the desired result of the same lie angle regardless of the position along the length of the grip that the player holds the putter.

FIGS. 11A-H illustrate eight alternative club grip cross-sectional shapes that may be used as an alternative to the elliptical club grip shown in FIGS. 6-10. The only requirement for the cross-sectional shape of the grip is that it has a width that will accommodate a channel that may be angled through the length of the grip. As shown in FIGS. 6-10, it may be elliptical. Various elongated shapes are shown in FIGS. 11A, 11D and 11E (ellipses with one or two flat sides), FIG. 11B (rectangle), FIGS. 11C (triangle) and 11F (hexagon). However, the grip may also be non-elongated such as FIG. 11G (circular) or FIG. 11H (square). In the case of a non-elongated shape, the dimensions of the grip must be such that the diameter of the channel is sufficiently smaller than the grip so that the channel may be formed at an angle through the grip.

The present invention may be embodied in other specific forms without departing from its spirit or essential characteristics. The described embodiments are to be considered in all respects only as illustrative and not restrictive. The scope of the invention is, therefore, indicated by the appended claims rather than by the foregoing description. All changes which come within the meaning and range of equivalency of the claims are to be embraced within their scope.

What is claimed is:

1. A self-balancing golf putter comprising:
a club head having:
a clubface configured to make contact with a golf ball;
a body on which the clubface is configured having:
a center of mass that is defined to be the point of intersection between an x-axis and a y-axis wherein the y-axis is parallel to the clubface and wherein the x-axis and the y-axis are in an x-y plane;
a lie angle radian defined to be through the center of mass, at an angle α_1 from the x-axis and having a measurable value greater than zero;

12

a lie angle axis that intersects the lie angle radian and is offset from and parallel to the x-axis; and
a radian plane parallel to the x-y plane; and
a shaft attached to the club head having:

a first end on which a grip is placed, a second end and a center axis running through the length of the shaft wherein the x-axis runs through the clubface at a negative x location on the x-axis and wherein the shaft is rearward leaning in a (-x, +y) quadrant of the x-y plane;

wherein the second end is attached to the body of the club head such that the center axis intersects the lie angle radian forming a balance point, and the center axis and the lie angle axis both lie in a lie angle plane; and
further wherein the lie angle plane and the radian plane form a lie angle α_2 that is approximately equal to the angle α_1 .

2. The self-balancing golf putter of claim 1, wherein the center axis of the shaft includes an axis of the shaft through a central portion of the shaft.

3. The self-balancing golf putter of claim 1, wherein the balance point includes an intersection of:
the lie angle radian; and
the lie angle axis.

4. The self-balancing golf putter of claim 3, wherein the body on which the clubface is further configured such that the lie angle axis includes a horizontal line approximately perpendicular to the clubface.

5. A self-balancing golf putter comprising:
a club head having:
a clubface configured to make contact with a golf ball;

and
a body on which the clubface is configured having:
a center of mass that is defined to be the point of intersection between an x-axis and a y-axis wherein the y-axis is parallel to the clubface and wherein the x-axis and the y-axis are in an x-y plane;

a lie angle radian defined to be through the center of mass, at an angle α_1 from the x-axis and having a measurable distance greater than zero;

a lie angle axis that intersects the lie angle radian and is offset from and parallel to the x-axis; and
a radian plane parallel to the x-y plane; and

a shaft attached to the club head having a center axis, wherein the center axis converges with a balance point formed at an intersection of an end point of the lie angle radian and the lie angle axis wherein the center axis and the lie angle axis both lie in a lie angle plane and the lie angle plane and the radian plane form a lie angle α_2 that is approximately equal to the angle α_1 wherein the x-axis runs through the clubface at a negative x location on the x-axis and wherein the shaft is rearward leaning in a (-x, +y) quadrant of the x-y plane.

6. The self-balancing golf putter of claim 5, wherein the balance point is at a position ($x=-x$, $y=\pm y_1$, $z=z_1$) in an imaginary Cartesian coordinate system defined around the club head, wherein the imaginary Cartesian coordinate system includes:

an origin at the center of gravity of the club head;
a z-axis defined as a vertical line through the origin;
wherein:

the x-axis passes through a toe of the club head and a heel of the club head;

13

- the heel of the club head has a negative y location for a right-handed player;
- a top of the shaft has a positive z location; and
- the radian plane is vertically offset relative to the x-y plane along the z axis
- wherein a position z_1 is the vertical distance between the origin and an attachment surface of the club head.
7. The self-balancing golf putter of claim 6, wherein the lie angle axis is defined by an intersection of the lie angle plane and the radian plane.
8. The self-balancing golf putter of claim 7, wherein the value of y_1 is calculated using the equation

$$y_1 = \left| \frac{Z_2 - Z_1}{\tan \alpha} \right|.$$

14

- wherein:
- z_2 is an offset between the radian plane and the center of mass, and
- z_2 is equal to zero.
9. The self-balancing golf putter of claim 7, wherein the value of x_1 is calculated using the equation

$$x_1 = \left| \frac{Z_2 - Z_1}{\tan^2 \alpha} \right|,$$

- wherein:
- z_2 is an offset between the radian plane and the center of mass, and
- z_2 is equal to zero.
10. The self-balancing golf putter of claim 6, wherein the vertical distance z_1 is between 0.4 inches and 0.6 inches.
11. The self-balancing golf putter of claim 10, wherein the vertical distance z_1 is approximately 0.5 inches.
